TYPE-WRITING MACHINE.

1,027,963.

Specification of Letters Patent.

Patented May 28, 1912.

Application filed December 20, 1906. Serial No. 348,745.

To all whom it may concern:

Be it known that I, CLIO B. YAW, a citizen of the United States, and resident of the borough of Brooklyn, city of New York, in the county of New York and State of New York, have invented certain new and useful Improvements in Type-Writing Machines, of which the following is a specification.

My invention relates to paper feeding mechanism for typewriting machines and has for its main object to provide an improved paper clamp or holder which is especially adapted to labels and other small work sheets.

To the above and other ends the invention consists in the features of construction, combinations of devices and arrangements of parts hereinafter described and particularly pointed out in the claims.

One form of my invention is illustrated in the accompanying drawings wherein—

Figure 1 is an enlarged front to rear vertical sectional view of a platen and platen carriage showing also the upper part of the machine on which the platen carriage is mounted, my invention being shown in place on the platen, the section being taken just at the right of the left-hand side bar of the platen frame. Fig. 2 is an enlarged fragmentary top plan view of the platen and platen frame showing the devices of my invention in place on said platen and also showing a paper finger on the platen carriage. Fig. 3 is an enlarged fragmentary

front view, partly in section, showing the platen and the paper clamp thereon as the latter appears when moved to inoperative position. Fig. 4 is an enlarged longitudinal sectional view taken centrally of the

platen and showing the left-hand side portion of the platen with my improved paper clamp in place thereon. Fig. 5 is an enlarged fragmentary perspective view of a part of the paper clamp, said part being

hereinafter termed a clamp carrier. Fig. 6 is an enlarged perspective view of another part of the paper clamp, said other part being hereinafter termed a clamp support. Fig. 7 is an enlarged perspective view of a 50 releasing member which operates to release the paper clamp or render it inoperative.

While I have shown the devices of my invention applied to a No. 6 Remington machine it should be understood that they may

be applied to other styles of typewriting machines.

In the drawings, 1 designates the top plate of the machine from which rise standards 2 supporting a back rail 3. Supported and guided on the rail 3 are rollers 4 mounted in a carriage truck 5 on which is pivotally supported a platen frame comprising a rear bar or rod 6, side bars 7 and a front bar 8. Mounted on the front bar is a wheel 9 which coöperates with a shift rail 10 carried on arms 11 which are pivotally supported on the main frame of the machine in the usual way. The parts above briefly described are found in the ordinary Remington typewriting machine and it is deemed unnecessary to describe them at greater length. The platen comprising the usual wooden core 12 and an inclosing rubber sheath 13 is rotatably mounted in the platen frame. Said platen is provided at the left hand with a platen head 14 which, as clearly shown in Fig. 4, is secured to the platen by wood screws 15 and has a central boss or hub 16, the latter being perforated to receive a short axle or shaft 17. The shaft is secured in the hub by a set screw 18 and passes outwardly through a bearing opening in the left-hand side bar 7 of the platen frame, said shaft at its outer end carrying the usual finger wheel 19. It will be understood that the right-hand end of the platen is provided with a platen head which is or may be of the usual construction; and that at the right the platen has a spindle or axle bearing in the right-hand side bar 7 of the platen frame.

My novel paper clamping device or paper clamp is adapted to be supported on the boss or hub 16 and to be secured or clamped against the outer face of the platen head 14 by a device presently to be described.

The main parts of the paper clamp or holder are shown in detail in Figs. 5, 6 and 7. The clamp comprises a clamp support shown in Fig. 6, said clamp support being formed preferably of a single piece of metal and comprising a plate-like body portion 20 and a hub 21. The clamp support is formed with a slot or cut-away 22 which enables the support to straddle and fit down over the hub 16 of the platen head, and the hub 21 of said clamp support is countersunk, as indicated at 23, to coöperate with a

securing device presently to be described. The sides of the hub 21 are formed with oppositely disposed bearing openings 24 which receive the reduced cylindrical bearing ends 25 of shouldered pivot screws 26, said screws 5 engaging tapped holes 27 formed in the sides of the body portion 28 of a clamp carrier, the latter being shown in detail in Fig. 5 and the screws 26 being clearly shown in 10 coöperation with both the clamp support and the clamp carrier in Fig. 1. The body portion of the clamp carrier is formed with a central circular opening 29 which fits over the hub 21 of the support and the lower portion 15 of the carrier is cut away as indicated at 30 providing a mouth for the opening 29 and enabling said carrier to be passed down over the hub 16 of the platen head. At the upper part of the body of the clamp carrier 20 is an arcuate flange 31 and immediately beneath the flange the body portion 28 is cut away to form an arcuate groove 32. The outer edge of the flange 31 is provided with an upstanding or outwardly projecting rib 25 33. Supported on the flange 31 and abutting against the rib 33 are a pair of finger-like clamping or gripping members 34, the shape of which is best shown in Figs. 2 and 3. Each of the members 34 is curved in 30 cross-section so as to conform to the curvature of the platen against which they are adapted to bear. These members or fingers are formed preferably of sheet metal and at their securing ends are provided with angular extensions 35 which conform to the shape of the flange 31 on which they are supported. The clamping fingers 34 are each secured in place on the clamp carrier 35 by headed screws 36 which pass through 40 suitable openings in the outer ends of the clamping finger and through an elongated slot 37 in the flange 31 and then engage with threaded openings in a clamping block 38 which is received in the groove 32 and abuts 45 the under side of the flange 31. The arrangement just described is clearly shown in Fig. 5. It will be understood that when the screws 36 are tightened they serve to draw the associate clamping block 38 up against 50 the under side of the flange 31 and thereby to frictionally secure the associate finger 34 in a fixed relation with the clamp carrier. By loosening the screws 36 the associate fingers 34 are freed so that they may be moved 55 bodily toward each other on the flange 31 until the parts 35 contact and away from each other as far as the slots 37 in said flange permit. The ends of the clamping fingers 34 abut the rib 33 and are held by 60 said rib from pivotal movement on the flange 31. Between the fingers 34 and below the flange 31 (as shown in Figs. 4 and 5) the clamp carrier is provided with a rectangular opening or slot 39 which receives a 65 releasing member or device 40 shown in de-

tail in Fig. 7, said releasing device being arranged in place so as to be held between the clamp support and the clamp carrier before these two parts are pivotally connected by the screws 26.

The device 40 is provided with a fulcrum pin 41 projecting from its sides and longer than the width of the slot 39 so that said pin may coöperate with the bottom and side of the groove 32 at the sides of the slot 39. 70 The inner face 40^a of the releasing member coöperates with the outer face of the body portion 20 of the clamp support in a manner presently to be described when said releasing member is actuated by a handle or finger portion 40^b which projects outwardly through the slot 39 so that it may be conveniently grasped by the operator. The arrangement of the releasing member with its fulcrum pin 41 inclosed between the clamp support and the clamp carrier is clearly shown in Figs. 3 and 4. The clamp carrier is pivotally mounted on the clamp support by the pivotal screws 26 as previously described and is normally maintained with the inner face of the body portion 28 pressed against the outer face of the body portion 20 of the clamp support by a pair of short coiled springs 42. The arrangement of these springs will be understood from a consideration of Figs. 1, 4, 5 and 6. Each spring has one of its ends seated in a depression 43 formed in the outer face of the body portion 20 of the clamp support, the depressions 43 being arranged one at each 90 side of the cut-away 22 and at the underside of the hub 21 as the parts appear in the drawings. The other end of each spring 42 is seated in a corresponding depression 44 formed in the inner face of a finger-like part 28^a which extends from the body 28 of the clamp carrier at the sides of the opening 30, the parts 28^a forming the lower portion of the circular opening 29 in the clamp carrier. As shown in Fig. 4 the inner faces of the 100 finger-like parts 28^a or those faces which are opposite the clamp support are beveled or inclined so that normally a V-shaped space or slot 45 exists at each side between the clamp support and the clamp carrier below 110 the pivot screws 26.

When the parts of the paper clamp (comprising the clamp support, the clamp carrier pivoted thereon, the clamping or gripping fingers 34 adjustably secured on said 120 clamp carrier and the releasing device 40) have been properly assembled, the paper clamp as a whole may be detachably secured on the hub 16 of the platen head 14 as will now be described. The hub 16 is exteriorly 125 threaded for the greater part of its length as shown in Fig. 4 and receives a clamping nut 46 having a knurled finger portion or head 47 by which the nut may be readily turned and thereby moved back and forth 130

along the hub 16. When screwed or turned forwardly the nut is adapted to move rightward along the hub and its inner end portion is adapted to enter the countersink 23 in the clamp support. To secure the paper clamp as a whole in place on the platen said paper clamp is passed down over the hub 16 and the clamping or thumb nut 46 is then turned forwardly as far as possible, thereby forcing the body portion 20 of the clamp support tightly against the exterior face of the platen head 14.

It will be understood that prior to tightening the thumb nut 46 the paper clamp may be arranged at any point circumferentially of the platen and of the hub 16 but that after said thumb nut has been tightened the clamp as a whole will be maintained in a fixed relation with the platen and will be rotated as the platen is rotated. It will further be understood that the inner end portion of the thumb nut 46 fits snugly in the countersink 23 when the nut 46 is screwed up tight as shown in Fig. 4 and that this arrangement prevents accidental displacement of the clamp as a whole radially of the platen. The outer or left hand face of the head 47 of the thumb nut is formed with a circular groove 48 (Figs. 1 and 4) which groove gradually increases in depth from its beginning 48^a to its end 48^b, which latter, as clearly shown in Fig. 1, is only a short distance from the beginning 48^a. The closed end 48^b of the groove is adapted to coöperate with a stop which, in the present instance, is shown in the form of a set screw 49 which projects from the hub 16 slightly to the right of the left-hand side bar 7 and is shouldered off to provide a flat inner face 49^a as shown in Fig. 4.

While the thumb nut may be turned on the hub 17 to release or free the paper clamp said nut is prevented from being moved far enough leftward to engage with the inner side of the left-hand bar 7 and thereby bind the parts so as to prevent turning movements of the platen, this prevention being caused by the coöperation between the end 48^b of the groove 48 with the forward side of the screw stop 49. The cut-away portion of the screw stop 49 permits the thumb nut to be turned so as to cause the groove 48 to pass over and partly embrace the top and right-hand side 49^a of the screw stop but before the bottom of the groove can contact with and bind against the flat face 49^a, the end 48^b of said groove will contact with the forward side of the screw stop 49 to prevent further turning movement of the nut 46 in one direction.

It will be understood that any other suitable means may be employed for preventing a binding of the nut 46 against the platen frame.

My invention is particularly adapted for

use with small work sheets such as the circular label illustrated in the drawings and designated by the reference character *a*. In employing said invention with a label like *a* the clamping or gripping fingers 34 are first adjusted or spaced apart as has been described until they are in their proper relation for holding the top and bottom edge portions of the label *a* against the platen. Assuming then that the paper clamp has been secured in place at the left-hand end of the platen by means of the clamping nut, the operator first preferably turns the platen until the paper clamp is uppermost as shown in Figs. 1 and 4 of the drawings and then presses down on the finger portion 40^b of the releasing member 40. This causes said releasing member to fulcrum on its fulcrum pin 41, the latter bearing against the bottom and side of the groove 32 on the clamp carrier, with the result that the face 40^a of said releasing member will be pressed against the outer face of the body portion 20 of the clamp support. As the finger piece 40^b is pressed downwardly the result of this action of the member 40 will be to overcome the springs 42 and swing the lower portion or arms 28^a of the clamp carrier toward the outer face of the clamp support about the pivot screws 26 and to swing the upper part of said clamp carrier away from the clamp support about the pivot screws, at the same time lifting the clamping or gripping fingers 34 upwardly and outwardly away from the surface of the platen. This pivotal movement of one part of the paper clamp on another part takes place about a pivotal axis at right angles to the platen axis and is permitted by reason of the slots or V-shaped openings 45 normally existing between the clamp carrier and clamp support below the pivot screws 26. Said pivotal movement it will be understood will be continued until the gripping fingers 34 have been swung away from the platen to the positions shown in Fig. 3 at which time it will be noted the V-shaped openings or slots 45 have been nearly closed and the springs 42 have been greatly compressed.

The gripping fingers 34 are preferably formed of spring metal and when in inoperative position as shown in Fig. 3 the inner or free ends of said fingers are preferably slightly inclined toward each other as shown by the dotted lines in Fig. 2. Holding the paper clamp open or in released position as shown in Fig. 3 with one hand, the operator may next place one of the labels *a* on the platen with the other hand and in position to be clamped by the fingers 34 when the finger piece 40^b is released and the rotary parts of the clamp are restored to operative position by the springs 42. During the return movement of these parts to operative

position the gripping fingers will contact with the top and bottom edge portions of the label *a* and will clamp said label tightly against the platen. The arrangement is such, however, that before the parts of the clamp are finally arrested the springs 42 will act to force the fingers 34 against the platen with sufficient force to overcome the inherent spring of the fingers so as to slightly spread the inner ends of said fingers apart until when the final arrest of the parts takes place said inner ends will be substantially parallel as shown by the full lines in Fig. 2. This spreading of the paper fingers is possible because of the inherent give or yield in the metal of which said fingers are made and is a valuable feature as it automatically spreads the portion of the work sheet or label *a* between said fingers with the result that the working portion is held tightly against the platen and any tendency to bulge or stand away from the platen is obviated and wrinkles will be smoothed out. The platen may now be turned by the operator in the usual manner until the label *a* is in position for enabling the first line thereon to be written.

Preferably one of the usual paper fingers 50 which is slidably mounted on the front bar 8 of the platen frame is used to facilitate the proper positioning of the label for writing. Said paper finger may be slid leftward along the front bar 8 until in the position shown in Fig. 2 just to the left of the edge of the label *a*. The clamping fingers on the latter are so thin and hug the platen so closely that they readily slide over the inner face of the paper finger 50 without obstructing the turning movements of the platen, nor will the other usual paper feeding and controlling devices and the usual platen scale obstruct said turning movements. The paper finger 50 is scored or cut as indicated at 51 to correspond with the writing line on the platen and when the platen carrier is lifted to expose the printing point on the platen the latter may of course be readily turned until the proper point for commencing writing on the label *a* is opposite the line indicator 51 on the paper finger 50. From an inspection of Fig. 2 it will be apparent that as the writing takes place the gripping fingers will hold the label on opposite sides of the writing or printing line and that they are substantially parallel with the direction of letter feed. After the label or work sheet *a* has been printed the platen may be turned and the label may be released by pressing down on the finger piece 40^b and another label may be clamped in place as has been described above.

If preferred the paper finger 50 may, of course, be slid rightward on the platen frame so as to be out of the path of the clamping or gripping fingers 34 and instead of turn-

ing the platen until the gripping fingers are at the top side thereof as shown in the drawings, the platen frame may be lifted to expose the writing after the label has been filled in, and then the gripping fingers may be released, the finished label removed and a fresh label inserted before the platen frame is swung down to resume writing. Or, if preferred, this method may be employed even when the paper finger 50 overlaps the gripping fingers 34 as shown in Fig. 2, although in such case additional pressure must be applied to force said paper finger away from the platen as the gripping fingers are swung away therefrom.

It will be seen that I provide a paper clamp or clamping contrivance of novel construction and which is very simple and efficient in operation; that said paper clamp may be readily arranged in place and as readily detached by the manipulation of the clamping nut 46; that said paper clamp is arranged at one side of the platen only; that the gripping fingers 34 extend lengthwise of the platen only part way along the platen and on opposite sides of and substantially parallel with the printing line when the writing takes place; that the gripping fingers are arranged substantially parallel with the direction of letter feed movements of the platen; that when in working position said fingers hold or clamp only the upper and lower portions of the label; that when the paper clamp is released the parts moved for this purpose (said parts comprising the clamp carrier and the clamping fingers, are given rotary movements about a pivotal axis on the stationary part of the clamp, which part has been called the clamp support, said pivotal axis being at right angles to the platen axis; and that during the rotary movements of the clamping fingers toward and away from the platen, said fingers, by reason in this instance of their inherent springiness, also are capable of a limited relative movement toward and away from each other, enabling the work sheet to be spread or smoothed out and caused to lie closely and snugly against the platen so that any tendency to wrinkle or bulge is obviated.

It will further be noted that I provide a paper clamp or paper clamping contrivance comprising a pair of gripping fingers which are relatively adjustable toward and away from each other and which also when brought into coöperation with the platen are adapted to be spread slightly apart and to be put under tension. This spreading action is due in the present instance to the fact that the platen is rounded or circular and exerts a wedging effect on the gripping fingers or, as they may be termed, gripping or clamping devices, when they are forced against the circular platen by their actuating spring or springs.

It will be understood that changes of various kinds may be made without departing from my invention.

What I claim as new and desire to secure by Letters Patent, is:—

5 1. In a typewriting machine, the combination with a platen, of a paper clamp comprising a member and a pair of gripping fingers on said member, said fingers being relatively adjustable toward and away from each other, and means for securing said member at one end only of the platen.

10 2. In a typewriting machine, the combination with a cylindrical platen, of a pair of clamping fingers adjustable relatively to each other circumferentially of the platen, each finger operating to clamp the paper between said finger and the platen.

15 3. In a typewriting machine, the combination with a cylindrical platen, of a clamping device comprising a pair of clamping fingers engageable directly with the paper to clamp it against the platen, which fingers when brought down upon the surface of the platen or the material to be written upon spread laterally, said clamping fingers remaining in clamping engagement with said material during the printing operation.

20 4. In a typewriting machine, the combination with a pair of clamping fingers engageable directly with the paper to clamp it, of a cylindrical platen adapted to wedge the fingers apart when they are brought down into clamping engagement with the paper, said fingers remaining in clamping engagement during printing operations.

25 5. In a typewriting machine, the combination of a pair of spring pressed clamping fingers engageable directly with the paper to clamp it and a cylindrical platen adapted to spread the fingers apart when they contact with the platen or the material thereon under the force of their actuating spring, said fingers remaining in contact with said material during printing operations.

30 6. In a typewriting machine, the combination of paper clamping devices, a spring for forcing them into contact with the platen and a cylindrical platen which acts with said spring to force said clamping devices slightly apart and put them under tension at the time the actuating spring is bringing them into clamping engagement with the platen or with the paper thereon.

35 7. In a typewriting machine, the combination with a pair of clamping devices, a cylindrical platen, and means for forcing the clamping devices down upon the platen and, together with the platen, causing the said fingers to spread apart and be put under tension.

40 8. In a typewriting machine, the combination with a platen, a pair of clamping fingers, a hinged support on which said fingers are detachably mounted, and means for forc-

ing the support toward the platen and the fingers down upon the platen.

9. In a typewriting machine, the combination with a platen, a hinged member supporting a pair of clamping fingers, and a spring for forcing the member toward the end of the platen and the fingers down upon the surface of the platen.

45 10. In a typewriting machine, the combination with a platen, a spring pressed support hinged at one end of the platen and provided with inwardly extending clamping fingers, and a finger piece adapted to act against said spring to move the hinged support away from the end of the platen and raise the clamping fingers away from the surface of the platen.

50 11. In a typewriting machine, the combination with a platen, of a label holder or clamp comprising a member provided with fingers arranged substantially parallel with the direction of letter feed and adapted, when the member is moved toward the platen, to clamp only the upper and lower portions of the label during the writing thereof.

55 12. In a typewriting machine, the combination with a platen, of a paper clamp arranged at one end of the platen and comprising a member provided with clamp parts which extend lengthwise of the platen and on opposite sides of the printing line when the writing takes place, the member being movable relatively to the platen to render the clamp parts operative or inoperative.

60 13. In a typewriting machine, the combination with a platen, of a paper clamp arranged at one end of the platen and provided with two clamp parts extending along the platen part way only of its length, one at each side of the printing line, a spring tending to constantly press said clamp parts toward the platen, and a finger piece operative on both said clamp parts simultaneously to move them away from the platen, overcoming said spring.

65 14. In a typewriting machine, the combination with a platen, of a paper clamp pivoted at one end of the platen and extending lengthwise of it, the pivotal axis of said paper clamp being at right angles to the axis of the platen and bearing a fixed relationship with the platen.

70 15. In a typewriting machine, the combination with a platen, of a paper clamp arranged at one end of the platen and comprising a pair of substantially parallel clamping or gripping fingers which extend along the platen part way only of its length and on opposite sides of the printing line when the writing takes place, and a spring operative to press said clamping fingers toward the platen.

75 16. In a typewriting machine, the combi-

nation with a platen, of a paper clamp detachably secured at one end of the platen and comprising a member provided with a pair of substantially parallel gripping or 5 clamping fingers which extend lengthwise of the platen and are normally spring-pressed toward the platen.

17. In a typewriting machine, the combination with a platen, of a paper clamp arranged at one end of the platen and comprising a pair of substantially parallel gripping fingers which extend along the platen part way only of its length, said fingers being relatively adjustable circumferentially of the platen.

18. In a typewriting machine, the combination with a platen, of a paper clamp pivotally connected with the platen at one end thereof and comprising a pair of substantially parallel gripping fingers which extend lengthwise of the platen, said fingers being adapted to be swung away from the platen about the pivotal axis of the paper clamp as a center, the pivot of said paper clamp being arranged at right angles to the platen axle.

19. In a typewriting machine, the combination with a platen, of a paper clamp pivotally connected with the platen at one end thereof and comprising a pair of substantially parallel gripping fingers which extend lengthwise of the platen, said fingers being adapted to be swung away from the platen about the pivotal axis of the paper clamp as a center, the pivot of said paper clamp being arranged at right angles to the platen axle, the clamping portion of said gripping fingers being constructed to spread in the act of engaging the platen.

40 20. In a typewriting machine, the combination with a platen, of a paper clamping contrivance pivotally mounted at one end of the platen and comprising a pair of substantially parallel gripping fingers which 45 extend along the platen part way only of its length, said fingers being adapted to be swung away from the surface of the platen and being resilient so that as they are swung away they spring slightly toward each 50 other.

21. In a typewriting machine, the combination of a platen, and a two-part paper clamping contrivance, one part of said clamping contrivance being secured at one 55 end of the platen in a fixed relation therewith and the other part of said clamping contrivance being hinged to the first part and comprising a pair of clamping fingers extending along the platen substantially 60 parallel with each other.

22. In a typewriting machine, the combination of a platen, and a two-part paper clamping contrivance, one part of said clamping contrivance being secured at one 65 end of the platen in a fixed relation with

said platen, the other part of said clamping contrivance being hinged to the first part and carrying a pair of clamping fingers which extend along the platen and are bodily adjustable toward and away from 70 each other on the part by which they are carried.

23. In a typewriting machine, the combination of a platen, a two-part paper clamping contrivance, one part of said clamping contrivance being secured at one end of the platen in a fixed relation therewith, the other part of said clamping contrivance being hinged to the first part and comprising a pair of clamping fingers extending along 75 the platen and substantially parallel with each other, and means tending to press said clamping fingers into coöperative engagement with the platen, said fingers being flexible so that under the influence of the 80 last named means they will separate or spread to a limited extent after contacting with the platen or the paper thereon.

24. In a typewriting machine, the combination of a platen, a two-part paper clamping contrivance, one part of said clamping contrivance being secured at one end of the platen in a fixed relation therewith, the other part of said clamping contrivance being hinged to the first part and comprising 95 a pair of clamping fingers extending along the platen and substantially parallel with each other, means tending to press said clamping fingers into coöperative engagement with the platen, said fingers being flexible so that under the influence of the 100 last named means they will separate or spread to a limited extent after contacting with the platen or the paper thereon, and a finger piece for overcoming said last 105 named means and swinging said fingers out of clamping engagement.

25. In a typewriting machine, the combination of a platen, a clamp support detachably secured to the platen at one end thereof, a clamp carrier pivoted to said support, substantially parallel clamping fingers adjustably mounted on said carrier, spring means tending to maintain said fingers in coöperative engagement with the platen, 110 and a finger piece for swinging said clamp carrier on its pivot and moving said fingers away from the platen.

26. In a typewriting machine, the combination of a platen having a head provided with a threaded portion or hub, a clamp support on said platen head, a clamping nut coöperating with the threaded portion of the platen head and adapted to clamp said support in a fixed relation with the platen, 115 a clamp carrier pivoted to said support, clamping fingers adjustably mounted on said carrier and substantially parallel with each other, and springs coöperating with said support and with said carrier to main- 120

tain said fingers in engagement with the platen or the paper thereon.

27. In a typewriting machine, the combination of a platen having a head provided with a threaded portion, a clamp support detachably mounted on said platen head, a clamping nut coöperating with the threaded portion of the platen head and adapted to clamp said support in a fixed relation with the platen, a clamp carrier pivoted to said support, clamping fingers adjustably mounted on said carrier and substantially parallel with each other, springs coöperating with said support and with said carrier to maintain said fingers in engagement with the platen or the paper thereon, and a finger piece for swinging said carrier on its pivots and thereby overcoming said springs and moving said fingers away from the platen.

10 28. In a typewriting machine, the combination of a platen, a slotted supporting member, a clamping or gripping finger on said supporting member, and a block arranged on said supporting member and connected with said clamping finger by a connection passing through the slot in said supporting member.

29. In a typewriting machine, the combination of a platen, a supporting member provided with a part having a slot, a paper gripping finger, a clamping block, and a screw connecting said clamping block and said gripping finger, said gripping finger and said clamping block being arranged at 35 opposite sides of the slotted part of the supporting member.

30. In a typewriting machine, the combination of a platen, a supporting member mounted thereon and having a slotted flange 40 or rib, a pair of gripping fingers arranged

at one side of said rib, a pair of clamping blocks associated with said fingers and arranged at the side of said rib opposite from said gripping fingers, and screws passing through the slots in said rib and connecting 45 said clamping blocks with said gripping fingers.

31. In a typewriting machine, the combination with a cylindrical platen, of a paper clamp comprising a pair of paper gripping 50 or clamping fingers, said fingers being relatively adjustable toward and away from each other, and said circular platen being adapted to wedge the fingers apart when they are brought into gripping or clamping 55 engagement.

32. In a typewriting machine, the combination with a cylindrical platen, of a hinged support, a pair of clamping fingers mounted on said support and adjustable toward and away from each other, and means for forcing said fingers into contact with the platen, the latter coöperating with said means to spread said fingers apart to a limited extent 60 and put them under tension.

33. In a typewriting machine, the combination with a platen, of a paper clamp arranged at one end of the platen and extending lengthwise of the platen and comprising connected pressure devices which 70 bear on opposite sides of the printing line when the writing takes place.

Signed at the borough of Manhattan, city of New York, in the county of New York and State of New York this 18th day of 75 Dec. A. D. 1906.

CLIO B. YAW.
